UNITED STATES PATENT OFFICE.

CASCIOUS H. DE LA MONTE, OF NEW YORK, N. Y., ASSIGNOR TO INTERNATIONAL MOTOR COMPANY, OF NEW YORK, N. Y., A CORPORATION OF DELAWARE.

DRAG-LINK.

1,376,383.

Specification of Letters Patent. Patented Apr. 26, 1921.

Application filed September 10, 1919. Serial No. 322,933.

To all whom it may concern:

Be it known that I, CASCIOUS H. DE LA MONTE, a citizen of the United States, residing in the borough of Manhattan of the city of New York, in the State of New York, have invented certain new and useful Improvements in Drag-Links, of which the following is a specification, reference being had to the accompanying drawing, forming a part hereof.

This invention relates to an improved drag link construction in which there is interposed between the steering arm and the steering knuckle devices for yieldingly transmitting the steering effort. In accordance with this type of construction, which is now well known, the steering arm is provided at its lower end with a ball which rests within sockets formed in spring-pressed blocks carried by the drag link and the drag link may be connected yieldingly at its other end in some similar manner to the steering knuckle. The present invention relates to a simple and inexpensive construction by which the said blocks may be secured within the drag link in such manner as to prevent their rotation and yet permit their ready assembling and disassembling. Reference is to be had to the accompanying drawing for a detailed description of the preferred embodiment of the invention, in which—

Figure 1 is a view in longitudinal section of a drag link embodying the improvements, the steering arm and knuckle arm being shown in one relation to the link, although it is evident that whether one or both of these arms extend upwardly or downwardly from the link as viewed is immaterial to the invention.

Fig. 2 is a transverse sectional view taken on the plane indicated by the line 2—2 of Fig. 1 and looking in the direction of the arrows.

Fig. 3 is a fragmentary detail view in plan taken along the plane indicated by the line 3—3 of Fig. 1 and looking in the direction of the arrows.

Fig. 4 is a transverse sectional view taken on the plane indicated by the line 4—4 of Fig. 1 and looking in the direction of the arrows.

The link a , which may be tubular, is formed at one end with a chamber a' to re-

ceive socket blocks b , c , in the proximate ends of which are formed sockets to receive the ball d on the end of what may be considered a steering arm d' . At the other end of the link a is formed a chamber a' to receive socket blocks e , f in the proximate ends of which are formed sockets to receive the ball g , on the end of what may be considered a knuckle arm g' . The sleeve a' is formed with an opening a'' of suitable form and dimensions to receive the ball d and the other sleeve a' is formed with a similar opening a'' to receive the ball g . In the illustrated embodiment the parts are so constructed and related as to cushion the steering effort when the link is moved longitudinally in one direction or the other. To this end the chamber a' carries at one end, say, the inner end, a socket block b on the rear wall of which is formed a guide boss b' the opposite end walls of which are milled off, as at b^2 , b^3 , to present opposed flat faces. The boss b' enters a socket member h which is of such form as to conform to the cross-sectional shape and area of the sleeve a' and is preferably made up as a stamping. In the form shown, this guide plate h has a central opening h' and in-turned ears h^2 at the opposite sides of said openings to bear against the flat faces b^2 , b^3 of the boss b' . At another section of the plate h , as on its periphery, are struck inwardly extending lugs h^3 which may rest in sockets a^5 formed in the end wall of the sleeve a' . Between the rear wall of the block b and the guide plate h is interposed operatively a spring i . By the construction described it will be evident that the parts may be readily assembled. The plate h has the lugs h^3 engaged with the sockets a^5 , the spring i is then inserted and finally the block b is positioned with the milled faces b^2 , b^3 resting within the central aperture h' in the plate h and engaging the flanges h^2 . This construction serves to permit axial movement of the block b and yet hold the block against rotation within the sleeve a' . The other block c may be threaded in the end of the sleeve a' until the ball d is properly positioned between the two blocks b , c when this block c may be locked in place by means of a stud k which passes through an annular clamp k' embracing the outer wall of the sleeve a' . The stud k rests

on a flat milled surface c' of the block c , so as to hold the block against rotation.

The construction for transmitting the steering effort yieldingly from the drag link

5 to the other arm g' is somewhat similar to that described, but differs in such respects as necessary for a complementary connection. At the other end of the drag link the block e conforming in cross sectional area 10 and shape to the sleeve a^2 is secured at the inner end of this sleeve in any convenient manner as by a through-pin l which may pass through the sleeve and the block. The other block f is yieldingly pressed against 15 the ball g . This block f has a rearwardly extending boss f' of reduced area and the rear end of this boss is milled at opposite sides, as at f'' , to present flat faces, which are engaged by the straight sides m formed in an 20 opening m' in a guide plate m^2 . This guide plate is held against rotative movement by providing, preferably, on its periphery, a lug m^3 which may rest within a slot a^6 formed in the sleeve a^2 . Between the guide 25 plate m^2 and the rear wall of the socket block f is interposed a spring n . In assembling the parts just described the block is inserted through the end of the sleeve a^2 , followed by the spring n and the guide plate 30 m^2 is then placed in position with the lug m^3 resting within the slot a^6 of the sleeve. The parts are held yieldingly in place by a plug cap o threaded in the open end of the sleeve, this plug being locked in position by 35 means of a stud p passing through an annular clamp p' encircling the outer end of the sleeve. The stud p , when in position, bears against the flat milled surface o' of the plug o in much the manner described in 40 connection with the block c and stud k at the opposite end of the link.

From the description given it will be evident that there is provided in the improved drag link only two movable socket blocks 45 b , f , and that these blocks are so related to the associated elements as to transmit the steering effort yieldingly, no matter in what direction the link is moved. The guide plates h , m^2 are of simple and inexpensive 50 construction and of such form as to permit the ready assembling of the blocks b , f and their associated springs i , n , respectively. The blocks are held positively against rotation by engagement of the guide plates h , m^2 55 with the bosses b' , f' on the respective blocks, and yet the blocks are permitted to have free axial movement as is necessary for the transmission of the steering effort yieldingly. The one end block c is held adjustably, in position but cannot move, in use, this block constituting the end plug for the sleeve a' . The other fixed block e is secured permanently against movement by the through-pin l .

60 The improved elements of the combina-

tion will be set out in the appended claims in such terms as will best indicate the scope of the invention.

I claim as my invention:

1. In combination with a drag link and 70 arm operatively engaged therewith, a sleeve at one end of the drag link into which the arm extends, a block of less diameter than the sleeve slidably mounted in the sleeve and engaging the arm, a guide plate independent of the sleeve and block and mounted in the sleeve, means to engage the block with the plate to hold the two against relative rotation while permitting relative sliding movement, and means to hold the plate 75 against rotation in the sleeve.

2. In combination with a drag link and steering arm operatively engaged therewith, a sleeve at one end of the drag link into which the arm extends, a block of less diameter than the sleeve slidably mounted in the sleeve and engaging the arm, a boss extending rearwardly from the block, a guide plate independent of the sleeve and block and mounted in the sleeve and having an 85 opening to receive the boss, means to engage the guide plate with the boss to hold the two against relative rotation while permitting relative sliding movement, and means to hold the plate against rotation in the sleeve. 90

3. In combination with a drag link and steering arm operatively engaged therewith, a sleeve at one end of the drag link into which the arm extends, a block of less diameter than the sleeve slidably mounted 100 in the sleeve and engaging the arm, a boss extending rearwardly from the block, a guide plate independent of the sleeve and block and mounted in the sleeve and having an opening to receive the boss, means to engage the guide plate with the boss to hold the two against relative rotation while permitting relative sliding movement, and a lug on the plate engaging the sleeve to hold the plate against rotation in the sleeve. 105

4. In combination with a drag link and arm operatively engaged therewith, a sleeve at one end of the drag link into which the arm extends, a block of less diameter than the sleeve slidably mounted in the sleeve 115 and engaging the arm, a boss extending rearwardly from the block and having flat surfaces milled on its sides, a sheet metal stamped plate independent of the sleeve and block and having an opening to receive the boss and provided with straight flanges to bear against the flat surfaces of the boss, and a lug stamped out of the periphery of the plate to engage the sleeve to hold the plate against rotation in the sleeve. 120

5. In combination with a drag link and arm operatively engaged therewith, a ball at the end of the arm, a sleeve at one end of the drag link in which the ball is disposed, two opposed socket blocks of less diameter than 130

the sleeve mounted within the sleeve and engaging the ball, a boss extending rearwardly from one of the blocks, a guide plate independent of the sleeve and block and mounted in the sleeve and having an opening to receive the boss, means to engage the boss with the plate to hold the two against relative rotation while permitting relative sliding movement, means to hold the plate

against rotation in the sleeve, a spring operatively interposed between the rear face of the block and the plate, and means to secure the other of said blocks in the sleeve and hold it against movement. 10

This specification signed this 8th day of 15 September, A. D. 1919.

CASCIOUS H. DE LA MONTE.
